MURDOCK MACDONALD, OF CLEVELAND, OHIO.

AUTOGRAPHIC REGISTER.

Application filed November 17, 1921. Serial No. 515,766.

The present improvements, relating as indicated to autographic registers, are directed more particularly to an improved type of register having improved means for registering the various sheets of paper as they pass over the writing-table portion of the machine. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

Fig. 1 is a longitudinal vertical section through my improved machine; Fig. 2 is a front elevation of the operating means for moving the sheets; Fig. 3 is a section on the line 3—3 in Fig. 2; Fig. 4 is a section on the line 4—4 in Fig. 1; and Fig. 5 is a plan view of one of the sheets showing the central registering slots.

My machine in general appearance, is similar to the autographic registers of the usual type in that it has a box-like casing 1, provided with a removable cover-plate 3, under which the paper strips 4, 5 and 6 are passed. The cover is open at the point 7, and a writing-table or support 8, is mounted beneath the paper at this point to serve as a firm support for the user in making whatever notes and memoranda are necessary on the uppermost sheet of paper. It will be understood that the usual carbon sheets are placed between sheets 4 and 5, and 5 and 6, these carbon sheets being passed transversely of the machine and held in suitable rollers or by other means which are not shown.

The paper is drawn through the machine and past the writing-table by means of rolls 9 and 10, which co-operate with each other to engage the papers and pull them forward upon rotation of the roll 10, by means of a suitable crank 11, and handle 12. After passing through these rolls, the two uppermost sheets of paper pass out over a support 13 and may then be torn off against an edge 14 on the cover, which is provided for that purpose, the lower sheet 4 then being stored in the forward compartment or portion 15 of the casing. The machine as so far described, is similar to the usual autographic register,

and my improvements relate to the means for storing and feeding the sheets through the machine, together with means for maintaining sheets in exact registration and for conveniently storing the lower sheet or strip of paper which is retained as a permanent record in the forward part of the machine.

Referring now to Figs. 1, 2 and 3, it will be seen that the roll 9 is provided with a recessed central portion 16, which lies opposite to the central portion of the roll 10, the latter roll being considerably shorter than the roll 9. Mounted in a recess in the outer wall of the roll 10, is a pivoted finger 17, provided with a small lug 18 about which is disposed a coiled spring 19, which operates against one of the walls of the recess in which the finger is mounted. This finger 17 projects upwardly beyond the outer surface of the roll 10 and is adapted to engage in narrow registering slots 20 formed at equidistant intervals in the paper strips 4, 5 and 6.

At the ends of the roll 10, or rather, at the ends of the shaft 21, on which this roll is carried, cams 22 are provided which engage against the ends of the shaft or roller 9, and act to lift this roller slightly away from the lower roller 10. The upper roller 85 is lifted at a sufficient distance to permit the grip of the two rollers on the sheets of paper to be released at the same time that the finger 17 is brought up to enter the slots 20 in the strips of paper. The lifting of the roll 9 is made possible by mounting it beneath springs 23 which serve to normally maintain it in frictional engagement with the roll 10.

In operation, the action of my machine is as follows. The handle 12 is turned to move the sheets of paper through the machine between the rollers 9 and 10, the strips of paper first having been properly positioned with respect to the rolls, so that the finger 17 will enter the slots 20 in the strips of paper. As the finger 17 is carried around by the roll and is about to enter the slots, the cams 22 lift the roll 9 and release the pressure on the paper so that the movement of the finger into the slots may center the several sheets of paper and bring them into exact registration longitudinally and transversely of the machine. The finger also serves to move these strips over the roll 10 until the cam 22 has released the upper roll and allowed the latter to again descend and

grip the strips. The strips are of course taut during their movement through the machine, and upon passing through the rolls, the finger 17 is pressed downwardly into its 5 recess in the roll 10 against the slight pressure of the spring 19.

Instead of employing the usual storage rolls for carrying the several strips of paper, I fold the three strips of paper together in 10 zig-zag or fan fashion, as indicated in Fig. 1, the paper being sharply creased at each fold. As the three strips 4, 5 and 6, are drawn through the machine, the paper automatically unfolds from the storage space, 15 while the sharp creasing serves to cause the lower strip 4 to again automatically fold itself in the same manner after it has passed through the feed rolls. This lower strip is carried over a small idle roll 25 which is 20 forward of the main feed rolls and is so positioned that each section of paper has sufficient space to fall clear and pile itself in the manner shown in Fig. 1. At suitable intervals, the restored strip may be removed 25 from the casing. The several strips are folded in the lengths which will be torn off upon each rotation of the handle 12, that is, each of the tickets or invoice slips is the 30 length of one of the folds of the paper in the machine.

In machines of this character, it has always been a matter of considerable difficulty to maintain the exact registration of the strips as they pass through the machine 35 and this is of course absolutely necessary, as otherwise, the printing of the various strips will not be in registration and the memorandum which is noted on the uppermost sheet, will not be reproduced at the 40 right places in the lower sheets. The present machine affords a very simple and effective means for maintaining exact registration between the various sheets. Each series 45 of tickets or slips are registered with each other as they pass between the feed rolls

and all possibility of a slight error entering into the registration and multiplying as the sheets go between the feed rolls, is avoided by the present construction. In addition to this, the fact that the sheets are not carried on storage rolls and are loosely folded together, facilitates the action of the registering finger in moving the sheets into exact registration if they happen to be slightly out of proper alignment as they pass between 50 the rolls. 55

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:— 65

1. In a machine of the character described the combination of a feed roller, provided with a peripheral recess, a spring-pressed finger mounted in such recess and normally projecting radially beyond the same, a second 70 roller, means normally maintaining the same in co-operative engagement with said first-named roller, and means acting to space said second roller from said first-named roller when said finger passes the same. 75

2. In a machine of the character described, the combination of a feed roller provided with a peripheral recess; a finger pivotally mounted in said recess about an axis parallel to said roller; a spring acting to keep said finger normally projecting beyond said roller; a second roller adapted to be normally engaged with said first named roller; and means acting to space said second roller from said first roller when said finger passes 80 the same. 85

Signed by me, this 1st day of November, 1921.

MURDOCK MACDONALD.
